UNITED STATES PATENT OFFICE.

JOHN T. McCACKEN, OF BRADFORD, KENTUCKY.

PIPE-COUPING.

1,077,417.

Specification of Letters Patent. Patented Nov. 4, 1913.

Application filed September 30, 1912. Serial No. 723,150.

To all whom it may concern:

Be it known that I, JOHN T. McCACKEN, a citizen of the United States, residing at Bradford, in the county of Bracken and 5 State of Kentucky, have invented new and useful Improvements in Pipe-Coupling, of which the following is a specification.

The present invention relates more particularly to couplings for air hose and the 10 like employed on railway cars, and the primary object is to provide a simple structure of a novel character that will automatically close the passageways when the members are detached and to automatically open the same 15 when the coupling members are brought into associated relation.

A further object is to provide means for properly guiding the parts into associated 20 relation in case they are slightly out of alinement.

The preferred embodiment of the invention is illustrated in the accompanying drawings, wherein:—

Figure 1 is a horizontal sectional view 25 through the coupling with the members in associated relation. Fig. 2 is a sectional view of the same on the line 2—2 of Fig. 1. Fig. 3 is a vertical sectional view through one of the members. Fig. 4 is a detail end 30 view, illustrating the arrangement of the spring.

Similar reference numerals designate corresponding parts in all the figures of the drawings.

In the embodiment disclosed, each coupling member is a duplicate of the other, and they are arranged horizontally at opposite ends of the car, so that each will always move into coacting relation with the member of an adjacent car. Each member comprises a body 5 having a projecting nose 6 at one end and a stem 7 at the other, to which the usual hose pipe is attached. The body is also provided at one side of the 45 nose with a recess 8 that receives the nose of the coacting member. Extending longitudinally through the stem 7 is the usual air passageway 9, which opens through one side of the nose, as illustrated at 10, and is preferably surrounded by a suitable packing gasket 11.

A reciprocatory valve 12 is slidable across the passageway 9, being mounted in suitable guideways 13, and preferably having 55 its margins or edges beveled as shown

at 14, in order to provide a better joint. This valve, when in open position, extends into the recess 8, as illustrated. A swinging valve-actuating arm 15 is located in the recess 8, being pivoted in the open end of the 60 same, as shown at 16, and having its rear portion slidably extending through a slot 17 formed in the outer end of the valve 12. A spring 18 is coiled about the pivot 16, and has two arms 19, one of which bears against 65 the wall of the recess, the other bearing against the arm. This spring serves to urge the valve to its closed position, as will be evident. Each of the projecting noses 6 of the member is provided near its end with 70 a transversely disposed rounded socket 20 that receives a similarly shaped projection 21 formed upon the adjacent side of the valve-actuating arm 15, the said projection engaging in the socket when the parts are 75 in assembled position, as illustrated in Fig. 1.

For the purpose of properly directing the members into coupling engagement, in case they are slightly out of alinement, guides 80 are employed, in the form of housings 23 slidably mounted on the bodies 5 of the members, and having flared open front ends 23. These housings have rear walls 25, against which bear coiled springs 24. The 85 springs 24 are shown in the preferred embodiment, as surrounding the stem 7 and being abutted against suitable stop collars 26, but any desired arrangement may of course be employed. Under ordinary conditions, the flared ends 23 are disposed in projecting relation, but when said ends are brought together, they will of course move rearwardly on the coupling members and against the action of the springs. This also 90 provides a good dust-excluder for the parts. 95

The operation of the structure is substantially as follows: When the members are separated, the springs 18 will act to move the valves 12 to closed positions across the 100 passageways 9, and will maintain them in said closed positions. When the members are brought together, however, the projecting nose 6 of each will enter the recess 8 of the other, and will engage the arms 15, 105 swinging the same outwardly, and thus causing the valves to move to open positions. When the members are in properly associated relation, the projections 21 will drop into the sockets 20 and thus secure the cou- 110

pling members against detachment, except when material strain is imparted to the same. It will thus be seen that simple means are provided for automatically controlling the passage of air or other fluid according to the relations of the coupling members. It will also be noted that the spring pressed arms 15 perform a still further function, in that they serve to press the noses toward each other, and thus insure a tight joint between the two that will reduce the danger of leakage.

From the foregoing, it is thought that the construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention.

Having thus fully described my invention, what I claim as new, and desire to secure by Letters Patent, is:—

1. In a coupling of the character set forth, the combination with coacting coupling members, each having a nose that extends alongside the other, said members having longitudinal passages that open through the coacting faces of the noses, a slide valve movable across the passage of each member and operating transversely of such member, and a valve actuating device disposed longitudinally of each member and having its outer end pivoted thereto in spaced relation to the nose thereof, the rear end of each actuating device being connected to the slide valve, the nose of each member entering the space between the actuating device and the nose of the other member and effecting the operation of the former.

2. In a coupling of the character set forth, the combination with coacting coupling members, each having a nose that extends alongside the other, said members having longitudinal passages that open through the coacting faces of the noses, a slide valve movable across the passage of each member and operating transversely of such member, a valve actuating device disposed longitudinally of each member and movable toward and from the nose thereof, the rear end of each actuating device being connected to the slide valve, the nose of each member entering the space between the actuating device and the nose of the other member and effecting the operation of the former, and a spring bearing against each valve actuating device for urging it toward the nose.

3. In a coupling of the character set forth, the combination with coacting coupling members, each having a nose that extends

alongside the other, said members having longitudinal passages that open through the coacting faces of the noses, a slide valve movable across the passage of each member and operating transversely of such member, a valve actuating device disposed longitudinally of each member and movable toward and from the nose thereof, the rear end of each actuating device being connected to the slide valve, the nose of each member entering the space between the actuating device and the nose of the other member and effecting the operation of the former, and a spring bearing against each valve actuating device for urging it toward the nose, the valve actuating device of one member and the nose of the other having interlocking engagements to hold the members against separation.

4. In a coupling of the character set forth, the combination with coacting coupling members, each having a nose that extends alongside the other, said members having passages therethrough that open and communicate through the opposing faces of the noses, a valve in each member controlling the passage therethrough, and valve actuating means for the valve of each member operated by the nose of the other member and bearing against the outer side of such nose, said means serving to urge the opposing faces of said noses toward each other.

5. In a coupling of the character set forth, the combination with coacting coupling members, each having a nose that extends alongside the other, said members having passages therethrough that open and communicate through the opposing faces of the noses, a valve in each member controlling the passage therethrough, and valve actuating means for the valve of each member operated by the nose of the other member and bearing against the outer side of such nose, said means serving to urge the opposing faces of said noses toward each other, and said actuating means furthermore interlocking with the noses to secure the members against separation.

6. In a coupling of the character set forth, the combination with coacting coupling members, each having a nose and a recess alongside the same, the nose of one member entering the recess of the other, said members having longitudinal passages and lateral outlets that open through the coacting faces of the noses, a slide valve movable across the passage of each member and operating transversely of such member, and a valve actuating arm disposed longitudinally in each recess and having its outer end pivoted therein in spaced relation to the said nose, the rear end of each arm being engaged directly with the said slide valve, the nose of each member entering the space be-

tween the arm and the nose of the other member and effecting the operation of the same, springs bearing against the outer sides of the arms to urge them against the nose, and thereby urging the noses against each other, and interlocking engagements between the noses and the arms to prevent the accidental separation of the members.

In testimony whereof I have hereunto set my hand in presence of two subscribing 10 witnesses.

JOHN T. McCACKEN.
